FRIDOLF HÖÖK, OF SAN FRANCISCO, CALIFORNIA.

Letters Patent No. 67,546. dated August 6, 1867.

IMPROVED MEANS FOR REEFING TOPSAILS.

The Schedule referred to in these Letters Patent and making part of the same.

TO ALL WHOM IT MAY CONCERN:

Be it known that I, FRIDOLF HÖÖK, of San Francisco city and county, State of California, have invented certain new and useful Improvements in Devices for Reefing Upper Topsails; and I do hereby declare the following description and accompanying drawings are sufficient to enable any person skilled in the art or science to which it most nearly appertains to make and use my said invention or improvements, without further invention or experiment.

The nature of my invention is to provide an improved device for reefing upper topsails, by which all the labor can be done from the deck of the vessel, and the necessity of sending men aloft will be avoided.

Travelling rollers are placed at intervals along the spar supported by the lower topsail-yard, and which support the spar and keep it from breaking, as well as keeping the sail properly in place. A reefing-chain having a sufficient number of turns about the rolling-spar passes in a sheave-hole in each end of the yard, and thence beneath the yard to a quarter block, from which it passes inside the rim of the top and through a single block, from which the tackle for reefing leads to the deck. To more fully explain my invention, reference is had to the accompanying drawings, forming a part of this specification, of which—

Figure 1 is a side elevation.

Figure 2, a front view.

Figure 3, an enlarged view of the travelling rollers.

Similar letters indicate like parts in each of the figures of the drawings.

A is the lower and B the upper topsail-yard. From each extremity of the yard A stout iron supports E, about fourteen inches long, project upward, having holes through the upper end. The journals of the rolling-spar C turn in these holes. The ends of the spar must be strengthened with iron bands. Battens are fastened along the spar, and a jack-stay, to which the foot of the sail is bent. These battens serve to take up the slack canvas as the sail is rolled up, and should not exceed in length the head-rope of the sail. Travelling rollers are placed so as to divide the spar into three equal parts, supporting it at each point of division to prevent it from breaking. These rollers are constructed in this manner: Side pieces of iron *a a* are bent so as to nearly encircle the spar, and made large enough to admit the sail rolling inside. These sides are firmly attached to each other, leaving sufficient space to admit the stout wooden rollers *c c c* which prevent the sail from chafing against the iron-work. The sides *a a* have attached, near their ends, a segment, composed of two parts, *d d*, and having the same curve as the sides *a a*. A stout iron crutch, *g*, attached to the yard A, clasps this segment, and has rollers *n n* on which the segment turns. The object of this is that when the sail is lowered suddenly, as in a squall, without furling, the apparatus will turn, so as to keep the opening through which the sail passes in the most favorable position for its entry, and thus prevent tearing, as would be the case if the rollers were rigid and stationary.

The reefing chain F passes both ends through the single block I I, from which they pass through the quarter block G, which is attached to the truss or to the lower topsail-yard A. The chain is then carried along both ways beneath the yard to the sheave-holes I I in the yard through which it passes, and has a sufficient number of turns around the rolling-spar C to roll the sail up by the unwinding of the chain. To the block I I is attached the tackle for working it, which leads to the deck. The tackle for hoisting the sail is shown at J.

The advantages of this method of reefing upper topsails are, first, the sail stands tighter because the foot is bent to the spar; second, the reefing is independent of the halyards; third, it requires no iron-work in the clews of the sail, neither reef-cingles nor reef-points, earings or gaskets; fourth, no buntline is required; fifth, it saves time; no alterations in the old rig are necessary except eyelet holes along the foot.

Having thus described my invention, I do not claim broadly the use of the rollers *c c* with their sides *a a*, nor the rolling of the sail in reefing; but what I do claim, and desire to secure by Letters Patent, is—

The crutch *g* attached to the lower topsail-yard, and its friction-rollers *n n*, together with the segment *d d* moving on said rollers, and attached to their sides *a a* substantially as and for the purpose described.

In witness whereof I have hereunto set my hand and affixed my seal.

FRIDOLF HÖÖK. [L. S.]
